US00D571065S

(12) **United States Design Patent** (10) **Patent No.:** **US D571,065 S**
(45) **Date of Patent:** **** Jun. 10, 2008**

(54) **VACUUM CLEANER**

(75) Inventor: **Gregory W. Luebbering**, Heyworth, IL (US)

(73) Assignee: **Electrolux Home Care Products, Inc.**, Cleveland, OH (US)

(**) Term: **14 Years**

(21) Appl. No.: **29/281,766**

(22) Filed: **Jun. 29, 2007**

(51) **LOC (8) Cl.** **15-05**

(52) **U.S. Cl.** **D32/31**

(58) **Field of Classification Search** **D32/22, D32/31-34; 15/321-322, 353, 324, 334, 15/347, 350-352, 415.1-422, 422.1, 361, 15/363, 374, 410-412; 34/84-85, 95.1, 633, 34/635, 638, 229**

See application file for complete search history.

CLAIM

The ornamental design for a vacuum cleaner, as shown and described.

DESCRIPTION

FIG. 1 is an isometric view of a vacuum cleaner showing the claimed design.

FIG. 2 is a front elevation view of the vacuum cleaner of FIG. 1.

FIG. 3 is a rear elevation view of the vacuum cleaner of FIG. 1.

FIG. 4 is a left elevation view of the vacuum cleaner of FIG. 1.

FIG. 5 is a right elevation view of the vacuum cleaner of FIG. 1.

FIG. 6 is a top plan view of the vacuum cleaner of FIG. 1; and,

FIG. 7 is a bottom plan view of the vacuum cleaner of FIG. 1.

The broken lines represent environment that forms no part of the claimed design.

1 Claim, 7 Drawing Sheets
